BY C. P. Goebel

ATTORNEY

UNITED STATES PATENT OFFICE.

MAX BRILL, OF NEW YORK, N. Y.

HAND BAG.

1,415,305.

Specification of Letters Patent. Patented May 9, 1922.

Application filed January 11, 1921. Serial No. 436,425.

To all whom it may concern:

Be it known that I, MAX BRILL, a citizen of the United States, and resident of the borough of Manhattan, city, county, and State of New York, have invented certain new and useful Improvements in Hand Bags, of which the following is a specification.

This invention relates to improvements in hand bags which combine the properties of an ordinary pocket-book and a receptacle for toilet articles such as a mirror, powder puff, powder box, etc.

The general object of the invention is the provision of a hand bag which has closable mouths or openings on opposite sides of the middle line of the bag and which give access to similarly disposed compartments in the bag, which compartments are normally out of communication with one another so that when either mouth is open only one compartment will be visible, but access however will be permitted to the opposite compartment without requiring that the bag be shifted or that the opposite mouth be opened.

To these ends the invention resides in a hand bag having a frame consisting of a middle and opposite side sections which are engageable with the middle section in the closed position of the bag, and a partition pivotally connected to the frame and detachably secured to the middle section and movable into spaced relation to either side of the middle section.

Other objects will appear and be better understood from that embodiment of the invention of which the following is a specification, reference being had to the accompanying drawings forming part thereof and in which:

Figure 1 is a perspective view of the invention in open position and with the partition swung to permit of communication between the compartments.

Figure 2 is a vertical cross-section of the device in the closed position.

Figure 3 is an enlarged detail side elevation of the connection between the flap and the middle section.

Figure 4 is a vertical cross-section on the line 4—4 at Figure 3.

Figure 5 is a detail side elevation of a portion of the closure for one of the compartments.

Figure 6 is a vertical cross-section on the line 6—6 of Figure 5.

Figure 7 is a horizontal cross-section showing a plan of the parts illustrated in Figure 5.

Figure 8 is an enlarged detail side elevation of the parts of the closure for one of the compartments.

Figure 9 is a vertical cross-section taken approximately on the line 9—9 of Figure 8.

The bag 5 may be formed of leather or other material found suitable for the purpose, and on its outer side and one face is provided a pocket 6. The mouth of the bag is connected to the substantially U shaped sections 7 and 8 of a frame which are preferably formed of metal and which function to provide a binding for the edge of the material of the bag 5. The pivots, one of which is shown and indicated by 9 connect the terminals of the sections 7 and 8 and permit swinging thereof in the opening and closing of the mouth of the bag. A middle or intermediate and substantially U shaped section 10 is connected to the pivots 9 and is formed throughout of metal. Section 10 is relatively wide in cross-section and its area is such as to permit the sections 7 and 8 to telescope therein and extend substantially flush with the edges thereof in the closed position of the bag. The middle portion of the section 10 is depressed longitudinally so as to provide a socket 11 in which is disposed a binding strip 12 of metal or the like on the inner end of the flap 13. The ends of the socket 11 are open to permit projection therethrough of extensions 14—15 of the binding strip 12 which are bent or clinched over the outer face of the socket 11 and thereby operate to secure the flap to the intermediate section 10 of the frame.

One surface of the flap 13 is faced with material corresponding to the outer facing of the bag 5 and, as shown in Figure 1, a mirror 16 or the like is arranged on the inner face of the flap. When the flap is in the closed position as shown in the Figure 2, it will extend over the pocket 6 and in this position it may be secured by any desired form of fastening means, such as a glove fastener, the elements of which are indicated by 17—18 as shown in Figures 1 and 2.

When the sections 7 and 8 are telescoped into the intermediate section 10 in the closed position of the bag, the said sections 7 and 8 abut on the opposite sides of the socket 11, which then functions as a stop to limit the inward movement of the sections 7

and 8. In the closed position of the mouths the male portions 19-19 of a pair of clasps shown in detail in Figure 9 and designated generally by "a" extend upwardly 5 through recesses 20-20 in the inner edges of downwardly and inwardly extending resilient plates 21-21 formed integral with or otherwise secured to resilient laterally extending plates 22-22 disposed on opposite side portions of the intermediate section 10. Each of the male portions 19 consists of a pair of knuckles in which are journalled the lateral extending portions 23-23 at the ends of the converging side 10 portions 24-24 which form the handle portions of a pair of operating levers of convenient size so as to be readily operatable by the fingers. Each lever may be formed of a single piece of steel wire bent so as to be substantially triangular in contour and offset at the point adjacent to the extensions 23-23 so as to provide a pair of shoulders indicated by 25-25 in Figure 9, the free end portion levers as shown in Figure 9 15 slope outwardly as indicated by 26-26 so as to permit of being readily grasped by the thumb and forefinger and moved upwardly and outwardly. When the parts are positioned as shown in Figure 9 upward and outward movements of either lever will cause the shoulder 25 thereof to impinge on the adjacent plate 21 and flex the same and also flex the intermediate section 10 of the frame and section to which the lever is attached, thereby causing a relative movement of the sections until the male members 19 are disposed below the recess 20, whereupon further turning movement of the handle on the shoulder 25 which fulcrums 20 on the side wall of the recess operates to move the section to which the lever is attached outwardly until the male members move beyond the lateral extension in which 25 position of the parts one side of the hand bag will be in the open position. A similar movement on the part of the opposite lever will effect the opening of the opposite side of the bag, so that the parts, except for the position of the flap 13, will then be as shown 30 in Figure 1.

The partition 27 shown in Figures 1, 2, 6 and 9 may be formed of any material found suitable for the purpose, and is herein shown as being flexible and is by preference faced with material corresponding to the material used for the lining of the bag, so as to present a fanciful appearance. The lower end of the partition is fixedly secured in any preferred manner to the middle portion 35 of the bottom of the bag 5 and the upper edge is provided with a substantially U shaped binding frame 28 formed of metal and pivotally connected to the sections 7, 8 and 10 at the pivotal point 9 thereof. 40 The area of the upper end portion of the

partition is such as to permit of its telescoping into section 10 and engaging therewith by means of a tapered knob 29 which enters a depression 30 herein shown as being located at the central portion of the lower outer face of the socket 11, all of which is clearly shown in Figure 9. The resiliency of the intermediate section 10 and the binding 28 is such as to permit of yielding engagement between the knob 29 and the socket 30 so that a pull by the fingers exerted on the binding 28 or pressure will disengage the partition from the position shown in Figure 9 and move the same to one side or the other of the intermediate section 10. 45 This construction is of importance, in that when one of the side sections, as for instance, the section on the left in Figure 2 is disengaged from the intermediate section and moved outwardly so as to give access 50 to the compartment indicated by 31 in Figure 2, access to the compartment indicated by 32 may be had simply by exerting a pull on the partition 27 until the same is disengaged from the intermediate section 55 thus rendering as unnecessary the operation of disconnecting the flap and operating the opposite handle which controls the mouth of compartment 32. In like manner and when compartment 31 is closed and compartment 60 32 opened, access may be had to compartment 31 simply by moving the partition 27 in the opposite direction or toward compartment 32. A pocket 33 may be provided in compartment 31 for a coin purse and a 65 number of pockets 35 may be provided on the partition 27 and arranged so as to face the compartment 32, for the reception of toilet paraphernalia such as a powder puff, powder box, and the like. Thus it will 70 be seen that in the event of desiring to make use of the toilet articles, and with the compartment 31 open the user may readily do so by disengaging the partition as previously described. And here too it may be observed, 75 use may be made of the mirror simply by detaching the flap 13 and turning the same over the open compartment 31, which, it will be observed, does not require the opening for the closure of compartment 32. 115

Although I have shown and described an ideal embodiment of my invention, it is to be understood that I am not to be limited to the structures herein shown and described, it being obvious that minor mechanical 120 changes may be made within the scope claimed, without departing from the spirit or sacrificing any of the advantages of the invention.

I claim:

1. In a hand bag a frame comprising an intermediate section and side sections disposed on opposite sides of the intermediate section and pivotally connected thereto, a partition section pivotally connected to the 130

- intermediate section and arranged so as to telescope therewith and be moved into spaced relation with either side thereof, and a flexible bag body secured to the said side 5 section and to the partition section.
2. In a hand bag a frame comprising an intermediate section and side sections disposed on opposite sides of the intermediate section and pivotally connected thereto, a 10 partition section pivotally connected to the intermediate section and arranged so as to telescope therewith and be moved into spaced relation with either side thereof, and a flexible bag body secured to the said 15 side sections and to the partition section, said side and intermediate sections having cooperating fastening devices for detachably securing the sections together when telescoped.
- 20 3. In a hand bag a frame comprising an intermediate section and side sections disposed on opposite sides of the intermediate section and pivotally connected thereto, a partition section pivotally connected to the 25 intermediate section and arranged so as to telescope therewith and be moved into spaced relation with either side thereof, and a flexible bag body secured to the said side 30 sections and to the partition section, said partition and said intermediate sections having cooperating fastening devices for detachably securing said parts together when telescoped.
4. In a hand bag, a frame including a 35 pair of oblong telescoping relatively rigid sections pivotally connected one to the other, the outer of said sections having a longitudinally disposed depression in its outer, face constituting a socket, the opposite ends of which are opened, and a binding element adapted to be connected to one 40 edge of a flexible flap and disposed within the socket and having its end portions extending through the openings thereof and 45 secured to the said outer section.
5. A hand bag comprising a main section, a pair of lateral sections hinged thereto and adapted to collapse thereagainst, means to latch the lateral sections with the main section, a partition section hinged to the main 50 section and adapted to telescope therewith and movable to either side of the main section, a bag body connected to the side and partition sections, said main and partition sections having means to latch the two together, and a flexible flap having one edge secured to the main frame and adapted to lie flat against one side of the bag body.
6. In a hand bag, a main frame of resilient material having integral latch means at 60 both sides thereof, a pair of side frames hinged to the main frame and adapted to telescope therewith, said side frames having means to engage with the latch means on the main frame when telescoped therewith, 65 means carried by said frames for springing the main frame therefrom to permit release of the side frames from said latch means, and a partition frame hinged also to the main frame and having relatively pivotal 70 movement with respect to the side frames, said partition frame and main frame having means therebetween for securing the two frames in telescoping relation.
7. In a hand bag, a frame including a 75 pair of oblong telescoping sections pivotally connected one to the other and formed of resilient material, the outer of said sections having a recessed lateral extension, the inner of said sections having latch means co-operating with said recessed lateral extension, a lever fulcrumed on the inner section and having an offset portion adapted to engage the said extension and flex the same to disengage the latch means when 80 the lever is turned in one direction.
- In testimony that I claim the foregoing as my invention, have signed my name hereunder.

MAX BRILL.
